[57] ABSTRACT

A four-phase logic delay circuit using two cascaded stages of field-effect transistors where each stage has two cascaded field-effect transistors for the storage of logic signals and two additional field-effect transistors for the isolation of the storage field-effect transistors for the duration of two phases of the four-phase signal.

FOUR-PHASE DELAY ELEMENT

The invention relates to a four-phase delay element comprising the cascade arrangement of at least a first and a second stage which each include at least a first and a second field-effect transistor, the source of the first transistor being connected to the drain of the second transistor, whilst the drain of the first transistor of the first stage and the gate of the second transistor of the second stage are connected to a storage capacitor, means being provided for applying a logical signal to the gate of the second transistor of the first stage, whilst the drain of the first transistor of the first stage is connected to a first clock-pulse line and the gate of this transistor is connected to a second clock-pulse line, the drain of the first transistor of the second stage being connected to a third clock-pulse line and the gate of this transistor being connected to a fourth clock-pulse line. These delay elements are particularly suited for use in dynamic four-phase logic systems such, for example, as shift registers. In a known delay element of this type the drain of the first transistor of the first stage is connected through the main current path of a field-effect transistor to the first clock-pulse line, whilst the gate of the latter transistor is also connected to this first clock-pulse line. The drain of the first transistor of the second stage is connected via the main current path of a field-effect transistor to the third clock-pulse line, whilst the gate of the latter transistor is also connected to this third clock-pulse line. In this known delay element the drain of the second transistor of the first stage is connected via the main current path of a field-effect transistor to the first clock-pulse line, and the drain of the second transistor of the second stage is connected via the main current path of a field-effect transistor to the third clock-pulse line. The latter feature has the disadvantage that in the operational condition of the delay element under certain circumstances the logical input signal may be incorrectly delayed, as will be explained hereinafter.

It is an object of the present invention to obviate this disadvantage and a four-phase delay element according to the invention is characterized in that the drain of the second transistor of the first stage is also connected to the third or to the fourth clock-pulse line and the drain of the second transistor of the second stage is connected to the first or to the second clock-pulse line, means being provided to isolate the source of the second transistor of the first stage from the first clock-pulse line during the application of clock pulses to the first and second clock-pulse lines, whilst further means are provided to, isolate the second transistor of the second stage from the third clock-pulse line during the application of clock pulses to the third and fourth clock-pulse lines.

An embodiment of the invention will now be described, by way of example, with reference to the accompanying diagrammatic drawings, in which

FIG. 1 is a schematic circuit diagram of a known delay element,

FIG. 2 shows voltage waveforms illustrating the operation of the delay element shown in FIG. 1.

FIG. 3 is a schematic circuit diagram of a delay element according to the invention, and

FIG. 4 shows voltage waveforms illustrating the operation of the delay element shown in FIG. 3.

The delay element shown in FIG. 1 comprises two stages I and II. The first transistor of the first stage is constituted by a field-effect transistor M_1 , and the second transistor of the first stage is constituted by a field-effect transistor M_2 . The gate of the transistor M_1 is connected to a clock-pulse line 2 which is connected to an output Φ_2 of a switching voltage supply S. The drain of the transistor M_1 is connected via the main current path of a field-effect transistor M_3 to a clock-pulse line 1, which is connected to an output Φ_1 of the switching voltage supply S. The source of the transistor M_1 is connected to the drain of the transistor M_2 , the gate of which is connected to the clock-pulse line 1. The drain of the transistor M_2 is connected via the main current path of a transistor M_4 to the clock-pulse line 1. The drain of the transistor M_1 is connected to a storage capacitor C_1 . A logical input signal V_i is applied to

the gate of the transistor M_2 . The first transistor of the second stage is constituted by a field-effect transistor M_5 , and the second transistor of this stage is constituted by a field-effect transistor M_6 . The gate of the transistor M_5 is connected to a clock-pulse line 4 which is connected to an output Φ_4 of the switching voltage supply S. The drain of the transistor M_5 is connected via the main current path of a field-effect transistor M_7 to a clock-pulse line 3, which is connected to an output Φ_3 of the switching voltage supply S. The source of the transistor M_5 is connected to the drain of the transistor M_6 , the source of which is connected to the clock-pulse line 3. The drain of the transistor M_6 is connected via the main current path of a transistor M_8 to the clock-pulse line 3. The drain of the transistor M_5 is connected to a storage capacitor C_2 , and the gate of the transistor M_6 is connected to the storage capacitor C_1 . The operation of the known delay element is as follows:

- It is assumed that the logical input signal applied to the gate of the transistor M_2 is a logical 1 ($-E$ volts) see FIG. 2c. During the time interval (t_1-t_2) the voltage at the output Φ_1 of the switching voltage supply S is equal to $-E$ volts, see FIG. 2a. During this interval the transistor M_4 will be conductive and the storage capacitor C_1 is charged until the voltage across it is $-E$ volts. During the said time interval the transistor M_4 also is conductive, so that a capacitance C_{s1} between the drain of the transistor M_2 and the substrate (earth) will be charged until the voltage across it is equal to $-E$ volts. During the time interval (t_2-t_3) the voltage at the gates of the transistors M_1 and M_2 is equal to $-E$ volts, see FIGS. 2b and 2c. As a result these transistors are conductive and the storage capacitor C_1 will be discharged during this interval until the voltage across it has become equal to 0 volts, see FIG. 2d. During the time interval (t_3-t_4) the voltage at the output Φ_3 of the switching voltage supply S is equal to $-E$ volts see FIG. 2e. As a result, the transistors M_7 and M_8 will be conductive. The storage capacitor C_2 is charged via the transistor M_7 until the voltage across this capacitor is equal to $-E$ volts, see FIG. 2g and a capacitance C_{s2} between the drain of the transistor M_6 and the substrate (earth) is charged via the transistor M_8 until the voltage across it is equal to $-E$ volts. The latter feature also means that the voltage across the series combination of the storage capacitor C_1 and a capacitance C_d between the gate and the drain of the transistor M_6 will be equal to $-E$ volts. Consequently, the voltage across the storage capacitor C_1 will become equal to

$$V_{c1} = -E \frac{C_d}{C_d + C_1} \text{ volts} \quad (1)$$

50

see FIG. 2d. During the time interval (t_4-t_5) the voltage at the output Φ_4 of the switching voltage supply is equal to $-E$ volts and this is also the voltage at the gate of the transistor M_5 . The voltage across the capacitance C_{s2} also $= -E$ volts. During the latter time interval the transistor M_5 will not be conductive, and the voltage across the storage capacitor C_2 will remain equal to $-E$ volts, see FIG. 2g. The latter feature holds only if it is ensured that the voltage across the storage capacitor C_1 according to the relation (1) remains smaller than the threshold gate voltage of the transistor M_6 . This means that C_1 must be much larger than C_d and that the voltage E must not be too high. However, in the cases where the capacitance value of the storage capacitor C_1 becomes comparable to that of the stray capacitance C_d , the transistor M_6 is likely to become conductive during the time interval (t_4-t_5) . As a result, the capacitor C_2 will be discharged to 0 volts, which means that the information stored in the capacitor C_2 (0 volts = logical 0) no longer corresponds to the information applied to the input of the delay element ($-E$ volts = logical 1), see the broken-line curve in FIG. 2g. As is known, the capacitance value of the storage capacitor determines the delay of the delay element. Because this capacitor, as has been described hereinbefore, must not be small, the known delay element is unsuitable for operation at high switching frequencies.

75

The delay element shown in FIG. 3 comprises two stages I and II. The first transistor of the first stage is constituted by a field-effect transistor M_1 , and the second transistor of this stage is constituted by a field-effect transistor M_2 . The gate of the transistor M_1 is connected to a clock-pulse line 2, which is connected to an output Φ_2 of a switching voltage supply S. The drain of the transistor M_1 is connected via the main current path of a field-effect transistor M_3 to a clock-pulse line 1 which is connected to the output Φ_1 of the switching voltage supply S. The source of the transistor M_1 is connected to the drain of the transistor M_2 the source of which is connected via the main current path of a transistor M_9 to the clock-pulse line 1. The drain of the transistor M_2 is connected via the main current path of a transistor M_4 to a clock-pulse line 3 which is connected to the output Φ_3 of the switching voltage supply S. The drain of the transistor M_1 is connected to a storage capacitor C_1 . A logical input signal V_i is applied to the gate of the transistor M_2 . The first transistor of the second stage is constituted by a field-effect transistor M_5 , and the second transistor of this stage is constituted by a field-effect transistor M_6 . The gate of the transistor M_5 is connected to a clock-pulse line 4 which is connected to the output Φ_4 of the switching voltage supply S. The drain of the transistor M_5 is connected via the main current path of the field-effect transistor M_7 to a clock-pulse line 3. The source of the transistor M_5 is connected to the drain of the transistor M_6 the source of which is connected via the main current path of a transistor M_{10} to the clock-pulse line 3. The drain of the transistor M_6 is connected via the main current path of a transistor M_8 to the clock-pulse line 1. The drain of the transistor M_5 is connected to the storage capacitor C_2 and the gate of the transistor M_6 is connected to the storage capacitor C_1 . The operation of the delay element according to the invention is as follows:

It is assumed that a logical 1 ($=E$ volts) is applied to the gate of the transistor M_2 , see FIG. 2c. During the time interval (t_1-t_2) the voltage at the outputs Φ_1 and Φ_2 of the switching voltage source S is equal to $-E$ volts, see FIGS. 2a and 2b. During this time interval, the transistor M_3 is conductive and the storage capacitor C_1 is charged until the voltage across it has become equal to $-E$ volts, see FIG. 2d. During the same time interval, the transistor M_9 of the second stage also is conductive. Consequently, a stray capacitance C_{s2} between the drain and the substrate of the transistor M_6 will be charged until the voltage across it has become equal to $-E$ volts. Since the charging of the storage capacitor C_1 and that of the stray capacitance C_{s2} take place during the same time interval, the voltage across the stray capacitance C_d between the drain and the gate of the transistor M_6 will be equal to 0 volts. During the time interval (t_2-t_3) the transistors M_1 and M_2 are conductive so that the storage capacitor C_1 is discharged until the voltage across it has become equal to 0 volts, see FIG. 4d. Since during the interval under consideration the voltage at the drain of the transistor M_6 is equal to $-E$ volts, see FIG. 4b, at the end of the said interval the voltage across the capacitance C_d will be equal to $-E$ volts. Consequently, during the said time interval no charge division between the storage capacitor C_1 and the stray capacitance C_d takes place. Hence, the voltage across the storage capacitor C_1 is independent of the ratio of the capacitance values of C_1 and C_d . Consequently, if a very fast delay element is desired, the storage capacitor C_1 may be given any desired small value (for example 0.01 pF). Further transfer of the information stored in the storage capacitor C_1 to the storage capacitor C_2 is analogous to the corresponding transfer of the information stored in the storage capacitor C_1 of the shift register shown in FIG. 1 to the storage capacitor C_2 of this shift register. For completeness, this is shown in FIGS.

4e to 4g. The source of the transistor M_6 is connected to the clock-pulse line 3 via the main current path of the transistor M_{10} . This is to prevent the transistor M_6 from becoming conductive in the phases Φ_1 and Φ_2 of the clock-pulse signal. The source of the transistor M_2 is connected to the clock-pulse line 1 via the main current path of the transistor M_9 . This is to prevent the transistor M_2 from becoming conductive in the phases Φ_3 and Φ_4 of the clock-pulse signal.

In the embodiment of the delay element according to the invention shown in FIG. 3, the drain of the transistor M_2 is connected to the clock-pulse line 3 via the main current path of the transistor M_4 . Alternatively, however, the drain of the transistor M_2 may be connected to the clock-pulse line 4 via the transistor M_4 . Similarly, the source of the transistor M_2 may be connected via the main current path of the transistor M_9 to the clock-pulse line 2 instead of to the clock-pulse line 1. The drain of the transistor M_6 may alternatively be connected via the main current path of the transistor M_8 to the clock-pulse line 1 instead of to the clock-pulse line 2. Similarly the source of the transistor M_6 may be connected via the main current path of the transistor M_{10} to the clock-pulse line 4 instead of to the clock-pulse line 3.

What is claimed is:

1. A four-phase delay element comprising the cascade arrangement of at least a first and a second stage which each include at least a first and a second field-effect transistor, the source of the first transistor being connected to the drain of the second transistor, the drain of the first transistor of the first stage and the gate of the second transistor of the second stage being connected to a storage capacitor, means being provided for applying a logical signal to the gate of the second transistor of the first stage, the drain of the first transistor of the first stage being connected to a first clock-pulse line and the gate of this transistor being connected to a second clock-pulse line, the drain of the first transistor of the second stage being connected to a third clock-pulse line and the gate of this transistor being connected to a fourth clock-pulse line, characterized in that the drain of the second transistor of the first stage is also connected to the third or the fourth clock-pulse line and the drain of the second transistor of the second stage is connected to the first or the second clock-pulse line, means for connecting the source of the second transistor of the first stage to the first or second clock-pulse line and for isolating the source of the second transistor from the second clock-pulse line during the application of clock pulses to the first and second clock-pulse lines and means for connecting the source of the second transistor of the second stage to the third or fourth clock-pulse line and for isolating the second transistor of the second stage from the third clock-pulse line during the application of clock-pulses to the third and fourth clock-pulse lines.
2. A four-phase delay element as claimed in claim 1, characterized in that the drain of the second transistor of the first stage is connected via the main current path of at least one third field-effect transistor to the third or the fourth clock-pulse line, the drain of the second transistor of the second stage being connected via the main current path of at least one fourth field-effect transistor to the first or the second clock-pulse line.
3. A four-phase delay element as claimed in claim 1, characterized in that the source of the second transistor of the first stage is connected via the main current path of a field-effect transistor to the first or the second clock-pulse line, the source of the second transistor of the second stage being connected via the main current path of a transistor to the third or the fourth clock-pulse line.
